UNITED STATES PATENT OFFICE.

WARREN B. HUTCHINSON, OF NEWARK, NEW JERSEY, AND SAMUEL M. FRIEDE, OF NEW YORK, N. Y., ASSIGNEES TO H. & F. MATCH MACHINE CORPORATION, OF NEW YORK, N. Y., A CORPORATION OF NEW YORK.

MATCH-MACHINE.

1,334,155.

Specification of Letters Patent. Patented Mar. 16, 1920.

Application filed March 30, 1918. Serial No. 225,628.

To all whom it may concern:

Be it known that we, WARREN B. HUTCHINSON, a citizen of the United States, and a resident of the city of Newark, county of 5 Essex, and State of New Jersey, and SAMUEL M. FRIEDE, a citizen of the United States, and a resident of the city, county, and State of New York, have invented a new and useful Improvement in Match-Machines, of 10 which the following is a full, clear, and exact description.

Our invention relates to improvements in match machines of the kind in which a continuous carrier is employed to dip 15 matches, and in which mechanism is used for inserting splints in the carrier. The object of our invention is to simplify and improve the construction of machines of this kind and particularly to improve the construction of the carrier to the end that it may be made cheaper and better, to provide 20 a simple means for driving the carrier in which the driving means also serves to hold it in the correct position for receiving match sticks and to permit the easy ejection of the sticks, to provide a simpler and better sticking 25 head for inserting sticks in the carrier, to provide means for ejecting the matches and at the same time putting them into their 30 own trays, and in general to make a better and more efficient machine of this type than has heretofore been constructed.

Reference is to be had to the accompanying drawings forming a part of this specification, in which similar reference characters indicate corresponding parts in all the views.

Figure 1 is a side elevation of that part of the machine called the station, in which the 40 sticking and ejecting takes place.

Fig. 2 is a broken view from the inside of the machine showing in front elevation the side of the machine in which the splints are inserted.

Fig. 3 is a broken plan view of the structure shown in Figs. 1 and 2.

Fig. 4 is a central vertical cross section showing the feeding, sticking and ejecting mechanism, the view being taken on an enlarged scale.

Fig. 5 is a diagram of the machine.

Fig. 6 is a front or face view of a part of the carrier.

Fig. 7 is a side elevation of a part of the carrier.

Fig. 8 is a cross section on the line 8—8 of Fig. 6.

Fig. 9 is a plan of the yoke or carriage from which the sticking and ejecting mechanism are operated.

Fig. 10 is a detail section showing the sticking head in a different position from that illustrated in Fig. 4.

Fig. 11 is a broken detail plan of a part of the boxing attachment, and

Fig. 12 is a detail of the cleaning comb.

Fig. 5 shows the general arrangement of the machine in diagram, in which A represents the station where the sticking and ejecting of the match splints and matches 70 occur; B represents the hot plate for heating the splints; C, the dipping means, and D the general course of the carrier for drying the matches. The organization illustrated in the diagram is not new, and on the 75 other hand the invention is not limited to any such arrangement and organization.

The carrier 10 is an endless carrier and it is formed of a series of narrow connecting bars 11 which are linked together, and 80 to this end each bar has on one side spaced apart and near its end portions, lugs 12, the pair of lugs 12 fitting between lugs 13 on the opposite side of the next adjacent plate as shown in Fig. 6, so that when the plates or 85 bars 11 are placed together, the lugs 12 will interlock with the lugs 13 and the several bars or plates are linked together by the pins 14. Rows of holes 15 occur in the bars or plates substantially as usual, to receive the match sticks 16. So far as the 90 structure of the carrier is concerned it is of course immaterial how the match splints are placed therein. The carrier is quite a departure from the ordinary practice in 95 making plate or bar carriers for matches.

Usually the plates or bars are made from plate steel or cast metal, and the holes are drilled accurately therethrough, while a milling machine is generally necessary to 100 provide feeding means at the ends of the bars, which means is sometimes a rack and pinion, sometimes a screw mechanism, etc. In our case, however, we make the bar narrow with the interlocking parts as stated, 105 and they are made from die castings, the holes 15, the holes 17 at the ends of the plates, and the holes for the pins 14 all being cast in the bars or plates. We find that this saves a very great amount of money in 110

building the carrier, and that the bars are actually better because the holes are all perfectly smooth and accurate.

The carrier is driven by means of pin wheels 19 having pins 18 thereon which enter transverse holes 17 in the ends of the plates 11. This makes a very simple driving mechanism, and by locating the pin wheels directly opposite the mechanism for injecting the match sticks and ejecting the matches, we gain a great advantage in match making. Usually rather a complicated feed mechanism is required for the carrier in order that the stretch and wear of the joints can be provided for and the holes in the carrier made to register accurately with the means for inserting and ejecting the splints or matches, but it will be noticed that in our case all this is unnecessary because no matter how much the carrier may stretch as a whole when the plates 11 are engaged by the pin wheels 19, the latter being intermittently moved as hereinafter described, hold the plates which are to receive the match sticks, or from which matches are to be ejected, in accurate position.

The pin wheels 19 are carried by a shaft 20 which is mounted in the main frame 9, and they can be driven in any usual way. We will presently refer, however, to the preferred means of driving them. Referring to Fig. 5, it will be noticed that the carrier driven by the pin wheels 19 passes up over the guide pulleys 22 and 23, thence downward beneath the pulley 24 and over the pulley 25, thence around the pulleys 26 and 27, thence over the pulleys 28 and 29 to dry in substantially the usual manner, thence back over the pulley 30 to the ejecting mechanism opposite the pin wheels 19.

As illustrated the pin wheels are driven by means of the ratchet wheel 31 which is secured to the shaft 20, and on the shaft is an oscillating arm 32 (see Fig. 1) carrying the pawl 33 to engage the teeth of the ratchet wheel 31. The arm 32 and the pawl are raised and lowered by the cam wheel 34 on the vertical shaft 35 which is mounted in suitable brackets 36 and 37 (see Fig. 2) and connects by means of bevel pinions 38 and 39 with the shaft 40 on which the driving pulley 41 is fixed. As will presently appear the moving parts of the machine are all driven from this shaft 35, but obviously the driving means is unimportant.

Extending centrally through the station A of the machine is a track formed of parallel rails 42 on the frame 9 of the machine, and on this track slides the arms 43 of the yoke or carriage 44 (see Figs. 4 and 9). At its front end the carriage serves to operate the sticking head shown in Figs. 4 and 10, and it carries a pusher plate 45 which is spaced apart from the carriage by a spacer block 46, and the pusher plate 45 slides over the

bed plate 47 which also has a sliding movement with the carriage and with the pusher plate 45, the inner end portion 48 of the bed plate being grooved as shown at 49 in Fig. 4 to receive the match sticks from the shaker 50 and from the hopper above. The bed plate is made in two parts 47 and 48 simply as a matter of convenience.

The carriage 44 is provided with holes 51^a through which extend the brackets 51 connecting with the bed plate 47 aforesaid, and the brackets 51 at their lower ends are connected to a cross rod 52 having tapered ends 53 (see Fig. 2) which slide in slots 54 (see Figs. 4 and 10) in plates 55 attached to the machine frame 9, so that the plate 47 has a guided and limited movement beneath the shaker 50. The carriage 44 can be moved in any convenient way, but we have shown the arms 43 provided with lugs 56 (see Fig. 4) connecting by rods 57 with eccentrics 58 on the shaft 59, and this shaft is driven by bevel pinions 60 and 61 connecting with the aforesaid shaft 35, and thus a reciprocating motion is imparted to the carriage.

The shaker 50 is substantially as usual in machines of this kind, having partition plates 62 vertically and transversely therethrough, and lying beneath corresponding plates 63 in the lower part of the hopper 64. The splints are inserted straight in the hopper and are further held by the springs 65 in the ends thereof, while the division plates 63 and 62 serve to keep them straight and deliver them straight to the grooves 49 of the plate 48.

There is a little lost motion between the carriage 44 and the bed-plate 47, because the slots 51^a are long enough to permit this. When the carriage begins to move back it will therefore move slightly before the inner walls of the slots 51^a engage the brackets 51, and move the bed-plate back. When the carriage reaches the limit of its stroke therefore, the parts will be in the position shown in Fig. 4, and with the grooved portions 49 directly beneath the shaker. This arrangement is such that the grooved parts do not at their inner ends come within the inner wall of the shaker, and so match sticks are prevented from wedging in between the plate and the shaker wall. This is important and facilitates the smooth working of the machine. When the reverse movement of the carriage takes place, the pusher-plate 45 will first move because of the lost motion above referred to, thus starting the splints smoothly from the grooves 49, and when the plate 46 reaches the plate 47, the two will move together to the position shown in Fig. 10, and the sticks will be smoothly and accurately inserted in the carrier.

The shaker 50 can be moved back and forth in any usual way, and we have shown

it provided with a projecting arm 66 (see Fig. 3) from which extends a cross arm 67, and the latter engages the teeth of a mutilated gear 68 on the shaft 35 so that by this means 5 the shaker is vibrated or reciprocated. Any other suitable means can be used, however. An abutment plate 69 is arranged behind the front member of the carrier (see Fig. 4) so as to stiffen the carrier against the thrust 10 of the sticking head.

To provide for cleaning the grooves 49 of the plate 48 from any slivers, broken splints, etc., we use a comb 70 which is vertically movable and the lower edge of which is 15 shaped to fit the grooved plate. This comb moves in slots 71 (see Fig. 4) and is held down by weights 72 (see Fig. 3) so as to fit snugly against the bed plate. The outer ends of the comb (see Fig. 3) ride on the 20 eccentrics 58, and so are raised and lowered with each stroke of the carriage 44, and the arrangement is such that the comb is lifted when the sticking head moves inward to press the splints in the carrier, and is 25 dropped on the return stroke so as to push any slivers or obstructions from the bed plate grooves.

The matches after being dipped and as they return on the opposite side of the station A, are ejected from the carrier by pins 30 74 which enter the inner ends of the holes 15, and these are carried by a cross bar 73 which can be mounted in any way but which as shown is suspended by arms 75 from a 35 rock shaft 76 (see Figs. 3 and 4). This rock shaft is supported on the machine frame in suitable bearings, and has a depending arm 77 having a loose connection by means of the screw 78 with a lug 79 on 40 one of the carriage arms 43.

It will therefore be seen by reference to Fig. 4 that when the carriage 44 moves inward to insert a row of match sticks in the carrier 10, it will at the same time actuate 45 the ejecting mechanism to force the pins 74 into the holes of the carrier and eject the finished matches from the carrier. This is an important improvement in the art and greatly simplifies machines of this character, 50 as a single sliding mechanism is thus made to operate both the injecting and ejecting devices whereby great economy of construction and accuracy of action are obtained.

Opposite the point where the matches are 55 ejected the carrier is backed by a grid 80 supported on brackets 81 fastened to the frame 9, and the grid has the horizontal plates 82 opposite the spaces between the holes 15 of the carrier and closely abutting 60 with the carrier, so that the grid serves as an abutment to stiffen the carrier against the thrust of the ejector, and the plates 82 separate the formed matches from each other. This arrangement of the grid, however, is not new except in connection with 65

the mechanism for putting the matches into trays. Below the grid is a slide plate 83 which is movable backward and forward and is like a comb, having members 84 which when the plate is moved lie alternately beneath the plates 82 of the grid 80 and beneath the spaces between the said plates, and the moving mechanism is timed so that when the matches are ejected from the carrier they will lie between the plates 75 82 and upon the members 84 of the plate 83. As the ejector is retracted, however, the plates 83 slide so that the matches drop between the members 84 and into the trays 88 which are arranged beneath the plate 83 to 80 receive the matches. The slotted plate 83 can be moved in any convenient way, and a simple way is to provide it with an arm 85 having a cam groove 86 therein which receives a pin 87 (see Fig. 3) on one of the 85 carrier arms 43. By the arrangement above noted it will be seen that the fall of the matches as they are ejected is interrupted by the members 84. When the matches are ejected the heads, because of their density 90 and smoothness are inclined to fall faster than the body portions of the splints, and if they fall direct into the trays they are quite likely to become disarranged, particularly if there should be the slightest movement of the trays; but where the fall of the 95 splints is interrupted by the members 84, the splints have an opportunity to straighten out between the arms of the grid 80, and then when the members 84 are suddenly removed they drop smoothly and evenly into the trays.

The trays 88 are held between the clips 89 of a horizontally moving belt 90 which moves across the machine below the point 105 where the matches are ejected, being guided by the plates 91 and 92, and the upper part of the belt moving over the guide table 93. The plates 91 and 92 and table 93 are suitably supported and serve as a framework 110 for the upper part of the box tray carrying belt. The belt 89 moves over suitable guide pulleys 94 and 94^a, and the shaft 95 of one of the upper pulleys is hung in a bracket 96 (see Fig. 1) and is provided with a ratchet 115 wheel 97 (see Figs. 1 and 2) which is engaged by the pawls 98 on the oscillating arm 99, the latter connecting by the link 100 with the eccentric 101 on the shaft 102, this connecting by gears 103 and 104 with the 120 shaft 35 already referred to. It will thus be seen that the belt 89 is given a step by step movement and the connection with the eccentric 101 can be an ordinarily adjustable one so that the stroke of the link 100 125 and the speed of the belt can be nicely regulated.

It is desirable to shake the upper member of the belt 89 a little so as to settle the matches in their trays. Any suitable means 130

can be used for this purpose, and we have shown a shaft 105 behind and parallel with the shaft 102, this shaft at its front end having a finger 106 connecting with the teeth 5 of the gear 103 so that as the finger rattles over the teeth, the shaft is rocked or trembled, and at its opposite end the shaft has a rod 107 slightly offset from the shaft and extending upward through the table 93 10 against the bottom of the belt 89.

From the foregoing description it will be seen that we have shown a very accurately operating and comparatively simple machine for the intended purpose, which will 15 continuously feed the match sticks to the carrier and continuously eject the matches into their containers, and while we have shown means for inserting splints from an ordinary hopper, it will be obvious that 20 many parts of the invention are not at all dependent on this idea of supplying splints to the carrier.

We claim:—

1. A match machine comprising an endless carrier having parts arranged to form 25 vertical legs or members movable in opposite directions, match splint inserting means opposite one leg of the carrier, match ejecting means opposite the other leg of the carrier, the inserting and ejecting means being in essentially horizontal alinement, a horizontal sliding carriage movable between the two legs of the carrier and in essential alinement with the inserting and ejecting means, 35 and mechanism connected to and moved by the carriage for operating both the inserting and ejecting means.

2. A match machine having an endless carrier with single vertical legs arranged 40 opposite each other and movable in opposite directions, match stick inserting means opposite one leg of the carrier, match ejecting means between the two legs of the carrier and operating to eject matches 45 from the second leg of the carrier, the inserting and ejecting means being in essentially horizontal alinement, a horizontal track between the inserting and ejecting means, a carriage sliding on the track, and 50 an operative connection between the carriage and the inserting and ejecting means whereby the two said devices are operated.

3. A match machine comprising a carrier 55 having two single vertical legs movable in opposite directions and spaced apart from each other, match stick inserting means opposite one leg of the carrier, match ejecting means opposite the second leg of the carrier, driving wheels having their axes in 60 essential alinement with the match inserting and ejecting mechanism, said wheels being located between the two legs of the carrier and directly engaging the carrier, a sliding carriage movable between the match stick inserting and match ejecting mechanism,

and an operative connection between the said carriage and the said match stick inserting and match ejecting devices.

4. In a match machine the combination with the carrier and the sliding carriage, 70 of the grooved bed plate adapted to receive match sticks moved by but to a less extent than the carriage, and a pusher plate movable with the carriage and the bed plate, said pusher plate riding on the bed plate 75 and adapted to force the match sticks into the carrier.

5. In a match machine the combination with the carrier, of a reciprocating bed plate having match receiving grooves in one part, 80 said bed plate moving perpendicular to the carrier, and a pusher plate sliding on the bed plate and adapted to engage the splints in the aforesaid grooves, said pusher plate having a first movement independent of the 85 bed plate, and a continued movement with the bed plate.

6. The combination with the carrier, of the match stick inserting mechanism comprising a grooved bedplate arranged perpendicular to the carrier and sliding back and forth in relation to the carrier, a sliding carriage opposite the bedplate, a pusher plate mounted on the bedplate behind the grooved portion thereof, said pusher plate 95 having a limited free movement on the bedplate and adapted through contact therewith to move the bedplate backward and forward, and a connection between the carriage and the pusher plate whereby the 100 movement of the carriage is imparted to the pusher plate.

7. The combination with the carrier, of the match inserting means comprising a support, a grooved bedplate slidable back and forth on the support and perpendicular to the carrier, a reciprocating pusher plate behind the grooved part of the bedplate, said pusher plate having a limited free movement with relation to the bedplate but adapted through contact with the bed plate to move 105 it, and means for actuating the pusher plate.

8. In a match machine the combination with the carrier having means for carrying matches in parallel relation perpendicular 115 to the carrier, and means for ejecting matches from the carrier, of a grid rigidly supported at its outer end and having inwardly extending members thin enough to enter between the rows of matches and with 120 the free ends of said members nearly in contact with the carrier, a slotted plate reciprocating directly below the grid, and a carrying belt movable below the said slotted plate.
